CLAIM

The ornamental design for an ear cleaner storage device as shown and described.

DESCRIPTION

FIG. 1 is a front, left and top perspective view of an ear cleaner storage device showing my design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the Ear cleaner storage device in an open configuration.

The broken lines are included for the purposes of illustrating portions of the ear cleaner storage device that form no part of the claimed design.
